(57) **CLAIM**

The ornamental design for a “hair brush,” as shown and described.

DESCRIPTION

FIG. 1 is a front, right side, and bottom perspective view of our new design for a hair brush.

FIG. 2 is a front view of the hair brush shown in FIG. 1.

FIG. 3 is a rear view of the hair brush shown in FIG. 1.

FIG. 4 is a right side view of the hair brush shown in FIG. 1, the left side being a mirror image thereof.

FIG. 5 is a top view of the hair brush shown in FIG. 1.

FIG. 6 is a bottom view of the hairbrush shown in FIG. 1.

FIG. 7 is a front, right side, and bottom perspective view of a second embodiment of our new design for a hair brush.

FIG. 8 is a front view of the hair brush shown in FIG. 7.

FIG. 9 is a rear view of the hair brush shown in FIG. 7.

FIG. 10 is a right side view of the hair brush shown in FIG. 7, the left side being a mirror image thereof.

FIG. 11 is a top view of the hair brush shown in FIG. 7; and,

FIG. 12 is a bottom view of the hair brush shown in FIG. 7.

The portions of the hair brush shown in broken lines in FIGS.

7, 9, 10 and 12 form no part of the second embodiment.

1 Claim, 8 Drawing Sheets
